ABSTRACT: There is disclosed herein an advanced solid waste disposal system comprising an open pit incineration arrangement for heterogeneous waste and refuse such as that collected by various municipalities and private organizations for disposal. In this incineration arrangement the heterogeneous refuse is fed into an open pit incineration chamber where it is transferred throughout the length thereof by an oscillating hearth. Solid materials not converted into gaseous products of combustion in this first traversal are recirculated within the open pit incineration chamber in the opposite direction by a second oscillating hearth and automatically returns to the first oscillating hearth adjacent the input to the incineration chamber. Such continuous recirculation continues until the material is substantially rendered into a state of incombustible solids. Grates or other waste removal devices are provided within the incineration chamber to allow removal of the solid incombustible materials left in the incineration chamber. Thermodynamic control is exercised to measure the flame

temperature within the open pit incineration chamber. The flame temperature is controlled so that a gas producer zone is provided adjacent to the oscillating hearths, wherein the waste is, in general, burned to products of incomplete combustion. Primary air is directed into the open pit incineration chamber from regions adjacent to the top thereof to establish a vortex having an axis substantially parallel to the direction of the travel of the waste on the oscillating hearth by a plurality of individually controlled air nozzles. A plurality of thermocouples or other temperature sensing devices are also provided to monitor continuously the flame temperature in different portions of the gas producer zone and, through appropriate control means, the air flow is responsively varied to maintain the flame temperature within a predetermined temperature range. Water cooled baffles are provided adjacent the top of the gas producer zone to separate it from the furnace zone. The baffles define an orifice through which the products of incomplete combustion move, in altered and reduced laminar flow characteristics, to the furnace zone for burning to products of complete combustion. Secondary air flow (natural, forced or induced draft) may be provided through the feed mechanism so that materials having a large surface area to mass ratio may be burned with great rapidity to products of complete combustion and/or gasify with increased rate into other carbon and hydrogen reactions. Many materials in this category will contain oxygen up to 30 percent. Under the above-stated conditions, no additional temperature sensing devices or air volume controls are required to offset the effect of secondary air penetrating into the length of the producer zone. The primary air temperature sensing devices automatically reduce the quantity of primary air delivered in inverse ratio to the increased availability of secondary air, in maintaining the proper quantity of total air required to maintain set-point temperature in any zone. Additional temperature sensing devices are provided in the furnace zone. Water spray through nozzles are used as auxiliary flame temperature control and are located adjacent to the primary air nozzles to provide a dousing stream of water for lowering the flame temperature in the gas producer zone in the event that the flame temperature should suddenly rise to a value greater than the predetermined temperature range. The heat of the flame is diluted in the conversion of water to steam. The heated gases of the products of complete combustion may be utilized as the heat source in a conventional steam generator-steam turbine power plant for providing electrical energy to drive the air compressor for the primary and secondary air flows as well as the mechanical power necessary for the feed and transfer mechanisms.

OPEN PIT VORTEX INCINERATION ARRANGEMENT

BACKGROUND OF THE INVENTION

Field of the Invention

This invention relates to an environmental pollution control system in the incineration art and more particularly to an improved arrangement for burning heterogeneous waste products to products of complete combustion.

Related Patents

This invention is an improvement of my invention of U.S. Pat. No. 3,465,696.

Description of the Prior Art

As noted in my above-mentioned patent, waste and refuse disposal, a major factor in world wide pollution control, is presenting increasing problems substantially throughout the world as the number of people in the world increases, as the concentration of people in limited geographic areas increases and as in the industrial civilization level rises throughout the world. Thus, the disposal of both solid and liquid refuse and/or waste products that are inevitably generated can no longer be handled in the traditional methods of waste disposal. That is, inefficient incineration cannot be utilized since the inefficient incineration often gives rise to smog or highly odoriferous gases emitted from the place of incineration. Land fill processes whereby solid and liquid waste and refuse are utilized to fill land which subsequently may be utilized for other purposes at best has only a limited applicability since the amount of land conveniently adjacent to the source of the waste and refuse is constantly dwindling as the population density increases and, further, the 40 to 50-year wait in time before such land is structurally stable so it can be utilized, for example, for buildings of one nature of another is often impractical. Additionally, the constant emission from such filled land of various gases adds to the smog problem as well as emitting noxious gases. Thus, the land is not stable or fit for human habitation until the end of 40 to 50 years when all organic materials have been broken down.

For example, in certain areas of California, filling land with solid wastes has been shown to produce more smog, higher temperature and more frequent and denser winter fogs and the loss of rain fall. Summer temperatures in certain areas, could rise by approximately 5° and drop by approximately 2° to 3° in winter. The summer temperature rise could result in a reduction of winds bringing relief to the western shores of the United States. Smog would increase because new land masses would produce more frequent temperature inversion which holds smog captive at ground levels.

The disposal of garbage by upstream water users has reached the point where water pollution as well as air pollution is a major problem. For example, in the City of San Francisco approximately 8 pounds per person of garbage is generated and San Francisco has traditionally dumped this garbage in the Brisbane area tide lands. The growing population in the Brisbane area has now made such dumping practices controversial and subject to Court litigation.

Additionally, the nature and characteristics of the waste and refuse is constantly changing. For example, waste and refuse once consisted primarily of garbage and ashes. However, now it may include dead animals, industrial wastes, demolition and construction refuse, old appliances, junk automobiles and machinery, glass containers, plastics, and the like. Thus, the waste and refuse may contain anything from a bed spring to a watermelon rind; from an automobile to a telephone pole with climbing cleats attached. While a 165,000,000 tons of solid waste was discarded nationally in 1966 in the United States, it is estimated that this amount will reach 260,000,000 tons by 1976. Further, the many important inorganic materials such as metals and the like, must be recoverable from the waste

disposal arrangement in order that shortages in such materials do not become prevalent. For example, by the year 2000 the United States population will be consuming as estimated 33.7 million tons of canned food and beverages each year, compared to only 16.7 million tons consumed in 1960. If most of these containers are not reprocessed, the can makers will run short of the primary can materials. In the year 2000, in the United States, it is estimated that some 474,000,000 tons of paper and paperboard will be used annually for packaging and there will be 3.2 billion pounds of rigid or molded glass or plastic used in packaging materials. Such glass or plastics are far more difficult to process efficiently in traditional waste disposal methods.

Combustion processes, therefore, remain as a major technique for disposing of solid and liquid waste. However, as noted above, combustion processes utilized for such waste disposal in the past are not now generally acceptable. There does not appear to be an awareness among many utilizers of such combustion waste disposals that the combustion process involved in the incineration of heterogeneous solid waste to a product of complete combustion is far more complex than that which is incurred in, for example, a heat engine. A heat engine can only use homogeneous fuels that have common limits of flammability and a predictable temperature-enthalpy and volume, in order to achieve a predictable performance with the designed product of combustion. Heterogeneous fuels, such as solid and/or liquid wastes, are not favorably endowed with the above-mentioned predictable characteristics. Therefore, heterogeneous solid and/or liquid wastes in order to become completely burned to a harmless state or to produce a predictable combustible product suitable for utilization in other systems: such as combustible gases that may be utilized in heat engines, heat exchangers or the like to make power, must be made into a gas that has been altered to have substantially homogeneous characteristics. The altered gases must have common limits of flammability, predictable and controllable temperature-enthalpy characteristics and controllable volume characteristics. This must be accomplished by automated control system since human operational judgment will generally not be sufficient to detect the changes necessary to achieve these characteristics.

The failure to understand the distinction between burning liquid and solid homogeneous and heterogeneous fuels is occasioned by the fact that the exploitation of heterogeneous fuels (that is, liquid and solid waste products) has never been economically or competitively required. Therefore, the incentive to understand the combustion process involved in burning heterogeneous feedstock was missing. However, because of the increased recognition of the ecological and health problems involved, there have recently been proposed many new techniques for alleviating the previously utilized but ecologically dangerous and/or unhealthy waste disposal techniques.

One type of solid waste disposal arrangement utilizes techniques for grinding the solid waste into small sizes prior to incineration. Such a technique, of course, merely reduces the size of the solid object that is to be burned, possibly increasing its surface area to volume ratio, but does not in any way alter the essential products of combustion resulting from the combustion of such a unit in a fixed incinerator arrangement.

Therefore, controls for varying the environment in which the combustion occurs are necessary to assure that the incineration arrangement achieves the desired result in burning all waste materials, ultimately, to products of complete combustion. The required controls need not be costly or complicated but the incineration process of heterogeneous solid and liquid waste must be understood to the extent that there is an awareness that controls are necessary. The probability of designing an incinerator that will insure the combustion of heterogeneous liquid and solid waste to a harmless product of complete combustion without the incorporation of such controls is practically nonexistent. It is as remote as, for example, designing a heat engine: e.g. internal combustion engine, gas

turbine, or a rocket, to have a predictable performance, without the control functions of a predictable and known fuel, lubricant, coolant and metallurgy. It simply cannot be done. Without temperature-enthalpy control and volume control incorporated in an incinerator design, the combustion process is one of anarchy and the products of combustion are in a thermodynamic, thermochemical, and fluid mechanical chaos. If either the calorific value of the combustible gases in the producer zone or the gaseous products of complete combustion in the furnace zone are to be fully exploited as a heat or power source, gas volume control must also be incorporated in the incineration process, whenever heterogeneous liquid and solid waste of varying calorific value and moisture content are incinerated. Since the above-mentioned category of solid and liquid wastes vary so extensively controls, therefore, must be provided in the incineration arrangement to achieve the desired designed combustion and economic performance.

It is inherent in combustion incineration arrangements that the limiting factor, generally, is not the feed rate of materials into the incinerator but rather it is the combustion or gasification rate of the material that is being burned. Any incinerator can, on a time basis, accept more solid waste than can be synthesized to a gaseous state, regardless of feedstock size. Therefore, the above-mentioned grinding and mixing of heterogeneous solid wastes prior to incineration is not only costly but will not substitute for efficient combustion temperature-enthalpy control in order to achieve a high production rate and a harmless product of complete combustion. Additionally, volume control may be incorporated for an efficient utilization of the gaseous product.

In general, it may be assumed that the production rate determination during incineration is confined to achieving a gaseous product of complete combustion. To achieve such complete combustion the maximum incineration rate of the liquid and solid waste is achieved when the steady state temperature is maintained so that the produced mixed gases, of the carbon and methane (hydrocarbon) equilibrium, have common limits of flammability. This means that the produced gases, then, can be completely burned with the same quantity of fresh air. Thus, starting with heterogeneous liquid and solid wastes, it is necessary to produce a commonality of the gases to have common temperature-enthalpy and volume characteristics. This means that the gases can be completely burned with the same quantity of air. Steady state set-point temperatures are to be achieved in spite of constantly varying calorific value and/or moisture content of the liquid and solid waste feedstock. If the mixed gases of the carbon and methane (hydrocarbon) equilibriums are produced at temperatures above or below that of the limited temperature range in which the gases are synthesized to be within common limits of flammability, much of the gases cannot be burned to a product of complete combustion. That part which is incompletely burned is an air pollutant.

Accordingly, it is necessary to burn, ultimately, the combustible materials to their products of complete combustion and leave the incombustible materials for further reprocessing to extract any desired material therefrom in as efficient and economic a process as possible. While the composition of both the solid waste as well as the liquid waste may be variable, the constituents thereof, though the percentages change, will be substantially the same. Therefore, by an analysis of the typical components on a weight basis from a large sample in any metropolitan area, it may be determined what the percentage of such constituents would be.

When such a material is burned in an incineration arrangement, desirably the residual would only be noncombustible inorganics and the products of complete combustion, namely ash, carbon dioxide, water and accompanying inert nitrogen. As noted above, however, traditional incineration arrangements generally resulted in incomplete combustion with the resultant emission of smog producing gases that may also be odorous and/or noxious. Such incineration arrangements were

often economically impractical since the investment in operational costs approached that of a manufacturing operation but in which no end product for subsequent sale is provided.

It is known, of course, that complete combustion of homogeneous gaseous fuels is readily achievable at atmospheric pressure, though complete combustion of solid and liquid fuels is not so readily attained at atmospheric pressure since they require, in general, higher pressures to achieve complete combustion. Thus, in an attempt to incinerate efficiently the heterogeneous waste and refuse, it has often been proposed to provide a chamber operated at greater than atmospheric pressure. The very inconsistency of solid wastes may either preclude its introduction into such a chamber or require the homogenization of the wastes by grinding or the like into fine enough particles so that, upon mixing, such wastes may be rendered substantially uniform in nature. Such grinding, as well as a pressure chamber for combustion is, of course, economically expensive and of limited size capabilities. Further, the control of both the temperature in turbulent mixing within the chambers can only be generally exploited for a specific and consistent homogeneous mixture.

Therefore, it is desirable to provide an incineration arrangement operating as an open pit or essentially at atmospheric pressure wherein heterogeneous liquid and solid waste and refuse may be economically fed and in which the combustible products thereof are, ultimately, burned to products of complete combustion.

SUMMARY OF THE INVENTION

Accordingly, it is an object of Applicant's invention herein to provide an improved open pit incineration arrangement.

It is another object of Applicant's invention herein to provide an incineration arrangement in which heterogeneous liquid and solid waste and refuse may be fed without prior classification or processing for incineration therein.

It is another object of Applicant's invention herein to provide an improved incineration arrangement in which combustible products are burned to products of complete combustion.

It is yet another object of Applicant's invention herein to provide an incineration arrangement that is economical to construct and operate.

It is yet another object herein to provide an economic system by the control of the volume of gaseous emissions from the improved incineration arrangement. Volume control permits the complete and efficient utilization of heat derived from constantly varying heterogeneous liquid and solid waste material.

The above and other objects are achieved, accordingly to one aspect of Applicant's invention herein, by providing both the structural elements utilized for an open pit incineration arrangement as well as appropriate thermodynamic and volume control thereof.

In one embodiment of Applicant's invention a waste and refuse input feed arrangement which, in this embodiment of Applicant's invention, may comprise an oscillating conveyor for receiving the heterogeneous waste and/or refuse from appropriate collection vehicles such as garbage trucks, trash collection trucks and the like, and the feed oscillating conveyor transfers the heterogeneous waste and refuse as received into a screw feed structure for transfer into an open pit incineration chamber. In the preferred embodiment of Applicant's invention, the screw feed arrangement is an Archimedean screw conveyor for transfer of the material from the feed oscillating conveyor into the open pit incineration chamber. The utilization of solid surface oscillating conveyor and Archimedean screw principles of conveyance is advantageous because these conveying mechanisms are not subject to being stopped by mechanical interference from any material conveyed upon or within the confines of their conveying surface. Both motions also have material classifying characteristics, reverse and vanning classification. Classification of material entering the

incinerator is conducive in this design to exploiting the high gasification rate of the bulk of material which statistically has a high surface to mass ratio. The characteristics of classification, also performs load-leveling for denser material, thereby forming a cohesive and consistent fire bed in the incinerator which is favorable to the exploitation of specific heats of material and the gasification of combustible solids. Both reverse and vanning classification assist in settling the ash out of the burning bed. The introduction of solid waste into the incinerator in the above described manner will reduce the quantity of particulate matter emitted in the flue gas because much of the finer and denser material is never airborne and furthermore is subjected to great cohesion and adhesions in the fire bed due to the more intense temperature experienced in this design than used in traditional incineration.

The cohesion and adhesion of particulate matter to the body of the fire bed is the result of almost invariable stickiness of both organic and inorganic material at temperatures in the range of 2000° F.

The open pit incineration chamber is essentially bounded by four walls and has an open top and a base. The base comprises a transfer arrangement of a solid surface oscillating conveyor hearth for moving the heterogeneous waste and refuse from the Archimedean screw feed discharge to the remote end of the open pit incineration chamber.

The conveyed burning waste material is delivered through the means of oscillating motion of the hearth up to a remote end of the solid surface oscillating conveyor hearth at the remote end of the chamber. Then the conveyed load has advanced to the remote chamber end wall and can advance no further and when it can no longer assume an angle of repose, it must then transfer into another area offering less resistance to movement or displacement. The area offering the path of least resistance is an adjacent and parallel solid surface oscillating conveyor hearth conveying in the opposite direction. The transfer is assisted by the use of a banked curve that is incorporated in the surface of the oscillating conveying hearth at the approach to the chamber end wall. The transferred conveyed burning material is then conveyed in the direction from whence it entered the incinerator. The conveyed burning bed is then transferred in the manner previously described into the path of the incoming unignited waste material and thereby, provides the initial ignition for unburned waste material at its inception into the incinerator. The remote or discharge ends of both solid surface oscillating conveyor hearths in the incinerator are identical in design and function. Any or all burning material and residue will automatically remain in recycle until removed.

It is assumed that a part of the solid waste introduced in the incineration chamber will not be completely reduced to incombustible objects by the time it has reached the remote end of the chamber. Thus, the design of Applicant's improved incineration arrangement permits the recycling of the unconsumed solid combustibles on the bed until they are completely reduced. Such solid products may be removed by a sliding grate that is incorporated into each section of the solid surface oscillating conveyor hearth. The sliding grate can be mechanically actuated to open or close to any desired opening size. The sliding member in either open or closed position is housed within the frame and support of the solid surface oscillating conveyor hearth. The sliding member is closed by moving in the same direction as the conveyed material while moving to closed position. The sliding member can move much faster in closing than can the rubbish being conveyed on it during closing movement. Therefore, because of the difference in the respective speeds of closing and conveying, the sliding member can, without interference, achieve a complete closure with the fixed end of the solid surface oscillating conveyor hearth in which it is housed.

The two sliding grates can be operated either separately or simultaneously to any predetermined or controllable aperture size desired. Any object that can be introduced into the furnace can be discharged from it without any mechanical interference.

The above short summary of the structure of Applicant's invention indicates the feed, transfer and discharge arrangements preferred by Applicant for his improved incineration arrangement. However, in order to achieve the proper combustion results, that is, the burning of the combustible materials to products of complete combustion, requires the thermodynamic considerations of the combustion characteristics of the waste and refuse.

Many disciplines in thermodynamics are required in burning the heterogeneous mass of combustibles in solid waste to a product of complete combustion. One, among the many disciplines required, is the utilization of recuperative heat.

The incinerator is a combination of a gas producer and a gas furnace and therefore utilizes recuperative heat in order to achieve the highest degree of efficiency in synthesis and production rate of gas. Heat is stored in the incinerator chamber walls refractory lining and in the fire bed on the hearth consisting of the ash and other noncombustible solid waste. The specific heats of noncombustible materials are exploited in order to sustain ignition temperatures of combustible materials and assist in maintaining temperature ranges required for the synthesis of gas from carbohydrates and hydrocarbons in the solids and liquids to the extent that common limits of inflammability can be established. This is required in order that a common fuel to air ratio can be established that will, ultimately, burn all of the component gases to a product of complete combustion.

The importance of exploiting the specific heat of materials 30 is based upon the heat transfer relationship that when hot and cold bodies are put in contact, the hot body transfers heat to the cold one until both reach the same temperature.

Many of the source materials for recuperative heat that are in solid waste have a low specific heat. This means that these 35 materials gain heat and lose heat slowly. Therefore, when such materials are ultimately heated, they provide a constant source of heat for a considerable period of time. Through contact, such a heat source is able to raise the temperature of most combustibles to a point where ignition occurs.

40 Examples of specific heats are as follows:

Water: 1; Iron: .113—118; Stone and brick: .192—.197; Paper and Wood: .600 approx.; Ash: .200—.250.

There are other factors effecting the production of a 45 product of complete combustion from heterogeneous solid and liquid waste. I.e., the reactions that take place in the gas producing phase within the open incinerator gas generator chamber are producer air gas and water gas reactions.

Water, when present, is in the liquid form. The heat of condensation of steam or water at 25° C. is represented by the 50 equation and typical gas reactions are shown in Table I:

A positive sign indicates that heat is evolved and a negative sign that heat is absorbed. The values are for the reactions at a 55 constant pressure.

TABLE I

GAS REACTIONS INVOLVED

	Reaction	Heat of Reaction Calories
60	$C + O_2 = CO_2$	+ 94 051.8
	$2C + O_2 = 2 CO$	+ 52 831.4
	$CO_2 + C = 2 CO$	- 41 220.4
	$2CO + O_2 = 2 CO_2$	+ 135 272.2
65	$2H_2 + O_2 = 2 H_2O \text{ (liq)}$	+ 136 634.8
	$C + H_2O \text{ (liq)} = CO + H_2$	- 41 901.7
	$C + 2H_2O \text{ (liq)} = CO_2H_2$	- 42 583.0
	$CO + H_2O \text{ (liq)} = CO_2 + H_2$	- 681.3

70 It should be noted that in order to have a reaction it is necessary that there be a physical union between the elements, i.e., in making CO_2 , C must be in the intimate presence of O_2 . This establishes the requirement for turbulence.

75 From the above data, it is obvious that heat must be stored in order to achieve practical incineration.

There are, under given physical conditions, both "lower" and "upper" composition - limits of inflammability. Within, but not outside these limits, self-propagation of flame will occur, once ignition has been effected.

The appropriate limits of inflammability of the pertinent gases, at ordinary temperatures and pressures are subject to these fuel to air ratios in producing a product of complete combustion in the furnace zone as shown on Table II.

TABLE II
FLAMMABILITY LIMITS
(% BY VOLUME)

GAS	LOWER LIMIT	HIGHER LIMIT
Carbon monoxide (CO)	12.5	74
Carbon-disulphide (CS ₂)	1.25	44
Hydrogen (H ₂)	4.0	75
Methane (CH ₄)	5.3	14
Ammonia (NH ₃)	5.1	70
* Producer Water gas	7.0	72
* Producer (Air gas)	17	70
* Blast furnace gas	35	74
* Mond's gas	4.0	72

* All of the above component gases in the make up of air and water gases have similar practical operating ignition characteristics with the exception of methane (CH₄).

The presence of moisture in solid waste will generate methane (CH₄) unless elevated temperatures are used. The fuel to air ratio for methane is not compatible with carbon monoxide (CO) and hydrogen (H₂) and therefore the methane must be changed to C + 2H₂ through elevated temperature in order to achieve the same fuel to air ratio required for burning carbon monoxide (CO) and hydrogen (H₂) to a product of complete combustion as shown on Tables III and IV.

TABLE III
PRODUCER GAS EQUILIBRIUM

2010	0.15	99.85			
2190	0.06	99.94			

The incinerator producer zone operating temperature range will be maintained between 2000° F. - 2500° F. and the furnace zone is maintained at a temperature between 2500° F. and the lower limit of spontaneous ignition. This lower temperature is on the order of 1000° F. - 1100° F.

Within this temperature range, the air or water gases generated in the producer zone will be synthesized to have common limits of inflammability, e.g. blast furnace gas or Mond's gas. The mixed or unmixed gases will be able to be burned to a product of complete combustion in the furnace zone on the basis of variable quantities of air being provided (volume per unit volume) that conform to the gas combustion requirements.

Flame temperatures vary with heat value of materials and the moisture content. When water is added into combustion processes or exists in the combustible material, flame tem

perature is reduced to the extent that heat is absorbed in changing water to steam. Air in relationship to flame has similar characteristics. If flame temperature is to be increased, the air quantity is reduced. If flame temperature is to be reduced, the air and/or water quantity is increased.

The control of flame temperature within the incinerator is not only important from the rate of production and the cost of maintenance aspects, but it also determined the constituency of the gases in both the producer and furnace zone.

10 For all gases, the maximum flame temperature is obtained when less air is used than required for stoichiometric or complete combustion.

This is illustrated in the following Table V showing some examples:

TABLE V
MAXIMUM FLAME TEMPERATURES OF GASES IN AIR

Gas	% of Gas in gas-air mixture giving maximum flame temperature	Maximum Flame Temperature °F
Carbon monoxide	34.00	3542
Hydrogen	31.60	3710
Methane	10.00	3416
Acetylene	9.00	4225

The control of temperature in the incinerator chamber is important because at elevated temperatures, there occurs a reaction that defeats the achievement of a product of complete combustion during incineration.

30 The reaction is "dissociation." At high temperature, the combustion of fuels is rendered incomplete because dissociation of carbon dioxide and of water vapor takes place, there being an equilibrium between CO₂, CO and O₂ and between H₂O, H₂ and O₂ on the other hand.

35 As temperatures increase above 2550° F., the CO₂ and H₂O gradually, at an increasing rate, reverts to CO, H₂, OH, O (atomic oxygen), H (atomic hydrogen), NO and N (atomic nitrogen). The dissociation reactions are essentially:

40 Therefore, temperatures within the furnace zone of the incinerator should be held below 2500° F.; if not, carbon monoxide and hydrogen will start to comprise much of the waste gas that is emitted into the atmosphere. The degree of emissions of products of incomplete combustion is shown in Table VI.

TABLE VI

Temp. °F	DISSOCIATION OF CARBON DIOXIDE AND WATER VAPOR

Flame temperatures, just like solutions, can be diluted. The effect of dilution can be illustrated as shown on Table VII: "Data Derived From the IT Enthalpy-Temperature Diagram." In the translation of maximum flame to flame temperature shown, it should be recognized that maximum flame temperature has approximately 90 percent—95 percent of the air that is the theoretical amount required for complete combustion. N = 1.2 excess air is an excess of 14 percent.

The completion of Table VII is based on two factors:

1. Statistical relationships exist among the net calorific value of all industrial fuels, their air requirements and the volume of combustion gas which they produce. These relationships render stoichiometric calculations based on ultimate analyses unnecessary and permit direct derivation of the initial enthalpy of any combustion gas.

2. For all industrial fuels, equal enthalpies of the theoretical net combustion gas, per unit volume, correspond to equal temperatures. Hence, the gas temperature may be directly derived from the enthalpy of the combustion gas or vice versa without recourse to the composition or specific heat of the gas.

The accuracy of calculations based on Temperature-Enthalpy Diagrams suffice for all practical purposes since the deviations are smaller than the errors inherent in technical sampling, in the determination of calorific values, analysis of gases, and in the measurement of temperature and volumes.

In the use of Temperature-Enthalpy Diagrams for the designing of combustion and auxiliary appliances, an excess-air factor must be assumed. In test plants, the factor must be calculated from the composition of the flue gas or derived in some other manner.

If only the gross calorific value of a fuel is known, the net value may be obtained from a table that is based on the results of the correlation of the gross and net values of a large number of solid and liquid fuels and is considered to be accurate to within ± 1 percent.

PROPERTIES, ANALYSIS, AND FORMULAS PERTINENT TO SOLID WASTE

A calorific analysis of typical combustible material in a solid waste dump reveals that on an average over a long period of time that the gross calorific value (C_{gr}) is approximately 6700 B.t.u. per pound.

In determining the heat value of solid waste, due consideration is given to the fact that there is a great difference in the calorific value of its combustible components, e.g., vegetable matter and asphalt. In the separate determinations of the heat value in the components of combustible waste, the percentage of paper and wood, generally constituting on the order of 67.5 percent of the approximate 82 percent total combustibles, indicated that, generally, the value for paper and wood approximately represents the average calorific value of the total

combustibles in solid waste.

Average Properties of Combustibles in Solid Waste based on the above is as shown on Table IX.

TABLE IX

Average Properties of Combustibles in Solid Waste

Moisture	15.0 %
Ash	2.0 %
Carbon	41.5 %
Hydrogen	5.1 %
Nitrogen & Sulfur	0.9 %
Oxygen	35.5 %
Volatile Matter	80.0 %
Calorific value, B.t.u./1b. Gross (C _{gr})	: 6700
Calorific value, B.t.u./1b. Net (C _n)	: 6000
Theoretical air requirement per lb. : 11.24	
Ft. ³ air at 32° F., 760 mm. Hg. (1 atm) : 62.24	
Waste gas - ft. ³ wet waste gas at 74.32	
32° F., 760 mm. Hg. (per lb. of fuel)	
CO ₂ content of dry waste gas	20.3 %

Wet Waste Composition

CO ₂	17.1 %
H ₂ O	15.6 %
Oxides of N & S	0.2 %
N ₂	67.1 %

With less moisture in the fuel, the composition of wet waste gas may be as follows by volume:

CO₂ = 17.5%

H₂O = 6.7%

N₂ = 73.8%

Dew Point ° F. : 130

Somewhat higher values were assigned to sulfur and nitrogen in solid waste to have a basis for describing the chemical reactions that will take place in incinerating material that may have sulfur and nitrogen content.

The properties of combustibles in solid waste were determined by consulting Charts on Average Properties of Solid Fuels, other than coal. The charts are based on the facts that

natural solid fuels have properties depending on their carbon and hydrogen contents and that so many of the properties are so interrelated that from a knowledge of two suitably chosen properties of any individual fuel, the others may be deduced with considerable accuracy:

- 35 Among these properties are:
 1. Volatile matter content;
 2. Calorific value;
 3. Moisture in air-dried fuel;
 4. Combustion characteristics: namely air requirements, volume, enthalpy, water-vapor content and carbon dioxide content of the flue gases and flame temperature.

40 It is essential that temperatures prevail at the furnace zone that exceed the minimum spontaneous ignition temperature of the gases that are to be burned to a product of complete combustion.

45 The gases generated in the producer zone will have the approximate minimum spontaneous ignition temperatures, at atmospheric pressure and with the proper air mixture ratios, as shown on Table X.

TABLE X
PRODUCER ZONE GAS IGNITION POINT

Gas	Ignition Temperature (°F)
55 Carbon monoxide	1060
Hydrogen	1040
Methane	1190
Ammonia	1200
60 Carbon disulphide	250
Hydrogen sulphide	560

65 Most solids that will be reduced to a gaseous state in the producer zone of the incinerator chamber will have relatively low ignition temperatures, i.e., 600 to 900° F. The minimum temperature for efficient combustion is probably 1000° F.

70 In order to achieve this predetermined temperature, in the preferred embodiment of Applicant's invention herein, Applicant provides in the producer zone, in a predetermined spaced array, a plurality of producer zone temperature sensing means, such as thermocouples, adjacent the top of the side wall in the producer zone of the incinerator chamber along the path of the first transfer oscillating conveyor. Operatively responsive to each of the producer zone thermocouples, there

is provided a producer zone air nozzle for directing a predetermined amount of producer air inwardly and downwardly into the open pit incineration chamber to establish a vortex air flow pattern therein. The vortex established by the producer zone air has a substantially horizontal axis, that is, aligned in a direction parallel to the direction of travel of the transfer oscillating conveyors. The amount of air flowing from each nozzle is individually controlled by its cooperative temperature measuring means in order that in each of the zones between the screw feed and the remote end of the open pit incineration chamber the flame temperature is maintained within the predetermined temperature range.

Further, in the thermodynamic considerations of Applicant's invention, the transfer oscillating conveyors contain a fire bed comprising a predetermined thickness of waste and refuse in various states of combustion. That is, for example, such a bed may be two feet or so thick and comprised of incombustible, ash, and combustible materials that have only been partially burned. Emanating from the fire bed, of course, is the flame in the open pit incineration chamber and it is the flame temperature that is measured by the thermocouples or other temperature measuring means provided. The fire bed and the flame together, may be considered a gas producing zone and in this zone it is desired to provide gaseous products of incomplete combustion from the solid combustible materials contained within the waste and refuse that is fed into the open pit incineration chamber.

While conventional gas producers attempt to maintain comparatively low temperatures so that combustible gases are produced thereby, in Applicant's invention, of course, materials having a high surface-to-volume such as newspaper sheets and the like, may be conveniently burned to products of complete combustion in the gas producer zone. However, within the controlled temperature range maintained in the gas producer zone, these carbon products of complete combustion take up additional carbon and evolve as CO. When water vapor (H_2O) is present in the reducing fire zone, the reaction is $CO + H_2O = CO_2 + H_2$. The CO_2 can take up additional C to make 2 CO. This reaction depends essentially on temperature maintained. Of course, material such as tree stumps, telephone poles and the like will, in general, according to the principles of Applicant's invention herein, not be combusted into products of complete combustion within the gas producer zone, but, rather, will be burned to products of incomplete combustion regardless of the number of passes through the open pit incineration chamber required. This is achieved by maintaining the temperature of the flame at such a value that a commonality of fuel-to-air ratio may be predicted based upon the statistical analysis of the contents of the waste and refuse and therefore the air flow adjusted to a predetermined amount in order that the flame temperature is maintained within this predetermined temperature range.

In the preferred embodiment of the present invention there is provided a water-cooled barrier having a predetermined shape and positioned between the above-mentioned gas producer zone and the furnace zone. In the furnace zone, the gases that are produced in the producer zone are burned to products of complete combustion. Preferably, the combustion in the furnace zone is also achieved at a preselected steady-state set-point temperature.

The above-mentioned barrier comprises baffles attached to the side walls of the incineration chamber at the top of the gas producer zone and, in effect, the baffles define the upper limits of the gas producer zone. The baffles present an orifice in which the exit area for the gases produced in the producer zone is reduced. The reduction in orifice area increases the escape velocity that is desired for gases entering the furnace zone and the subsequent heat exchange area. The predetermined shape of the baffles provides a means for controlling the flame elongation in the producer zone. Additionally, the physical separation provided by the baffles shapes the gases in the producer zone into a laminar flow gas pattern. Laminar flow is conductive to making controllable, long, luminous

(reducing) flames and thereby providing uniform temperature distribution throughout the producer zone. Such uniform temperature distribution in the producer zone adds greatly to the life of the refractory materials utilized to line the producer zone.

It has been found that the increased surface area provided by the baffles between the producer zone and the furnace zone provides an additional impingement surface for entrained particulate matter in the gas stream that follows the periphery or side walls of the producer zone. Particulate matter, having mass, tends to be thrust due to centrifugal force outwardly to impinge upon the side walls of the incineration chamber defining the producer zone. The shape of the baffles is selected to provide a profile that tends to maintain the integrity of the vortex flow pattern to achieve this centrifugal force upon the particulate matter. The orifice area provided by the baffles provides an additional barrier for particulate matter entrained in the producer gas to inhibit the entrance of such particulate matter to the furnace zone. Particulate matter entrained in the producer gas laminar flow pattern, having mass, must lose inertia in order to deviate and rise at a right angle into the furnace zone. To do so, the escaping particulate matter must then further penetrate the producer zone air stream. Both of these actions are difficult for such particulate matter to achieve and, therefore, most particulate matter will be retained in the producer chamber for recirculation within the producer zone. The baffles are preferably water cooled in order that refractory roof, bridge walls, arches or the like may be eliminated from the structure defining the incineration chamber. This tends to reduce considerably the initial cost of construction as well as subsequent maintenance and repair.

It has been found that structural separation provides a plurality of advantages in actual operation. Such structural separation between the furnace zone and the producer zone provides a structure for allowing utilization of special techniques for controlling and changing gas velocities. The furnace zone size can be reduced due to a more rapid and positive means of changing the combustion atmosphere from a reducing to an oxidizing state. The orifice size and location can be selective whereby the highest and localized gas escape velocities through the unrestricted cross-sectional area of the orifice can be brought down closer to the average escape velocity. The above-mentioned gain in retention of particulate matter in the producer zone is achieved since the gases are prevented from entering the furnace zone en masse through laminar flow with the bulk of the gas having an excessively high escape velocity and the remainder of the gas having an extremely low escape velocity. Even though the average escape velocity may be acceptable, unevenness of gas flow tends to prevent a good mixing with the air in the furnace zone.

There are provided a plurality of furnace zone temperature sensing elements each controlling an adjacent furnace zone air nozzle that provides air into the furnace zone for the combustion of the gases to products of complete combustion. The furnace zone temperature sensors providing the control to the furnace zoned air are independent of the temperature sensing functions and control functions achieved in the producer zone and thus the two air supplies, even though they may be from a common header, are independently controllable so that independent control of the set-point temperature for combustion in the producer zone and in the furnace zone may be achieved regardless of the varying calorific value of solid waste feedstock.

Hydrocarbon and carbohydrate gases and vapors of varying calorific content are the normal resulting products from combustion of liquid and solid waste, having varying calorific value, in the producer zone. The present invention has the capability to synthesize these gases, through temperature control, in order to have the same enthalpies and common limits of inflammability (volume per volume with air) to make a product of complete combustion. However, different volumes of gases having the same enthalpies per cubic feet require dif-

ferent quantities of air that are commensurate with their respective volumetric requirements to make a product of complete combustion in the furnace zone. As a means of explanation, methane equilibrium refers to gases of the so-called hydrocarbon chain. Methane (CH_4) is the lowest in order of the hydrocarbon chain. Methane requires less air than any other hydrocarbon to achieve its highest temperature and it is lowest in calorific value. Methane has a minimum requirement of 9.5 parts of air to 1 part of methane to be burned to a product of complete combustion. Ethylene (C_2H_4) has a minimum requirement of 14.28 parts of air to 1 part of ethylene to be burned to a product of complete combustion. Ethane (C_2H_6) has a minimum requirement of 16.66 parts of air to 1 part of ethane to be burned to a product of complete combustion. Their respective B.t.u. content per ft.³ is 995, 1560 and 1730. The respective B.t.u. content per ft.³ of CO and H₂ is 318 + 320 and their respective minimum air requirements are both 2.38 - 1.

Among the gases that normally evolve from heterogeneous liquid and solid waste fuels in the producer zone are methane (CH_4), ethylene (C_2H_4) and ethane (C_2H_6). These gases, when evolved in a temperature range between 2000° F. and 2550° F., will have common limits of inflammability among themselves and with CO and H₂. For example, the synthesis that permits this will be methane (CH_4) to $\text{C} + 2\text{H}_2$, ethylene (C_2H_4) to $2\text{C} + 2\text{H}_2$ and ethane (C_2H_6) to $2\text{C} + 3\text{H}_2$. All of the

above gases can then be burned to a product of complete combustion with a common fuel to air ratio. Other hydrocarbons and carbohydrates will essentially follow the same pattern. Any part of these combustible gases that are not altered to have common limits of inflammability will not be burned to a product of complete combustion. The above-stated, altered gases per unit volume will now have the same air requirement as CO and H₂, namely, a minimum requirement of 2.38 parts of air to 1 part of gas in order to be burned to a product of complete combustion. This condition will exist for the altered gases in an air-gas mixture that is within the wide and parallel limits of inflammability that exist for CO and H₂. The air-gas mixture in the furnace zone will determine the temperature and enthalpy (calorific value of the gas per unit volume) for combustion to a product of complete combustion.

However, when the gas has achieved steady state temperature and enthalpy and the attendant capability of being burned with a common fuel to air ratio to a product of complete combustion, there remains another problem in burning the gas to a product of complete combustion in the furnace zone. The volume of gas generated in the producer zone will vary directly with the calorific value of the constantly varying calorific value of the liquid and solid waste fuel for a given set-point temperature maintained, as shown by Table XIII, XIV, XV, XVI and XVII.

Note: Air Factor = 1.0 is air required to burn 1 pound of waste product.

Therefore, it does not insure that the varying volumes of gas can be burned to a product of complete combustion in the furnace zone with a fixed quantity of air. The limits of inflammability of CO and H₂ are wide, but may not be sufficiently wide to encompass the great variance in volume encountered in steady-state temperature and enthalpy gases that can be generated from heterogeneous liquid and solid waste.

It is for the above reason that temperature should also be sensed in the furnace zone in order that the proper volume of air be provided to insure that the varying volumes of com-

65 bustible gas can be burned to a product of complete combustion. As a precautionary effort, temperature control should also be used in the furnace zone to insure that any gas volume is not provided with an over-sufficiency of air which would prevent spontaneous ignition temperature. An example of air quantity effect upon furnace temperature is shown in Table VII, under furnace zone.

To indicate the air requirements and the attendant volumes of gas comprising CO₂, H₂O and N₂ that are in the resultant product of complete combustion in the furnace zone, note the

respective quantities of air and gases that are indicated in Table XI.

5	Gas (1 ft. ³)	BTU/ft. ³	COMBUSTION PRODUCTS				Total Ft. ³ (wet)
			Air Req'd	CO ₂	H ₂ O	N ₂	
	CO	318	2.38	1.00	---	1.88	2.88
	H ₂	320	2.32	---	1.00	1.88	2.88
	CH ₄ to C + 2H ₂	995	9.52	1.00	2.00	7.52	10.52
	C ₂ H ₄ to 2C + 2H ₂	1560	14.28	2.00	2.00	11.28	15.28
10	C ₂ H ₆ to 2C + 3H ₂	1730	16.66	2.00	3.00	13.16	18.16

The original calorific value (B.t.u. content) of a gas determined the quantity of air required to burn it to a product of complete combustion, even if synthesis has occurred where common limits of inflammability have been established with other gases. It is obvious that even if 1 ft.³ of C₂H₄ is changed to an elemental mixture of 2C + 2H₂ more air will still be required to make a product of complete combustion than is required in making a product of complete combustion from 1 ft.³ of CO.

Therefore, as described below in greater detail, for the present statistical analysis of waste and refuse products Applicant prefers to provide a flame temperature in each region of the gas producer zone of the open pit incineration chamber as determined by the plurality of temperature measuring means within a range of 2000° F. and 2500° F. Above this temperature, it is indicated, there will be disassociation of certain of the products of combustion. Below this temperature, of course, the products of complete combustion will not be generated but rather products of incomplete combustion will be allowed to be emitted into the atmosphere.

In certain embodiments of Applicant's invention, Applicant prefers to provide a conventional steam powered electric generator arrangement for providing energy to power the compressor needed for the air supplies, the control arrangements, and the energy needed for operating the various mechanical structures. Heat exchangers, deriving heat from the incinerator flue gas, provide the steam source. The steam power generator may drive other power sources such as electric motors.

In the preferred embodiments of the present invention, the above-mentioned incineration arrangement may be effectively combined with expansion chambers, heat exchangers and gas scrubbers and absorbers to ensure that the gases emitted into the atmosphere are nonpollutant gases.

BRIEF DESCRIPTION OF THE DRAWINGS

FIG. 1 is a block diagram of Applicant's approved incineration arrangement;

FIG. 2 is a perspective view thereof;

FIG. 3, 4, 5, and 6 are sectional views of portions thereof;

FIG. 7 is an end sectional view thereof;

FIG. 8 is an isometric view thereof; and

FIGS. 9, 10 and 11 are sectional views of portions thereof.

DESCRIPTION OF THE PREFERRED EMBODIMENTS

Referring now to FIG. 1 there is shown a block diagram of one embodiment of Applicant's improved open pit vortex incineration arrangement. The block diagram in FIG. 1 indicates both the flow characteristics as well as the thermodynamic and structural arrangements necessary in the practice of Applicant's invention herein.

As shown in FIG. 1, there is an open pit incineration arrangement generally designated 10, according to one aspect of Applicant's invention. There is provided a refuse and waste input feed arrangement 12 that transfers a heterogeneous

mass of waste and refuse into an open pit incineration chamber 14. The waste and refuse within the open pit incineration chamber 14 is subjected to predetermined thermodynamically controlled combustion as controlled by the temperature measurement, feed rate, air and water control means 16. The open pit incineration chamber 14 is also provided with a solid incombustible material output 18 for removal of solid incombustibles from the open pit incineration chamber. Further, gaseous products of complete combustion generally indicated by the arrow 20 leave the open pit incineration chamber.

An air supply 22 which, of example, may be an air compressor, is utilized to supply both air in response to the control 16 as well as secondary air to the waste and refuse input feed arrangement. In this embodiment of Applicant's invention an electric motor 24 is utilized to drive the air supply 22 and power for the electric motor 24 is provided by a conventional steam generator-steam turbine arrangement indicated at 26 comprising the steam generator 28, the steam turbine 30 and the condenser 32 for driving an electrical generator 34 that provides the electrical energy to drive the electric motor 24 as well as for all internal control arrangements and mechanical drives as required by the input feed or in the open pit incineration chamber 14. It will be appreciated, of course, that the arrangement shown for the embodiment of Applicant's invention illustrated in FIG. 1 is substantially independent of any outside source of power. That is, the completely self-contained unit may be conveniently located wherever desired without reference to appropriate power supply requirements.

In order to more fully understand and appreciate Applicant's invention herein, Applicant will describe first the structural elements comprising Applicant's improved open pit incineration arrangement and then will describe the thermodynamic controls imposed thereon for burning waste and refuse.

THE WASTE AND REFUSE INPUT FEED

40 There is shown, referring now to FIG. 2, a perspective view of a schematic representation of Applicant's improved open pit incineration arrangement. As shown on FIG. 2 the waste and refuse input feed means 12 is comprised of a feed oscillating conveyor 36 that receives on the upper surface 38 thereof unclassified and heterogeneous liquid and solid waste and refuse from the appropriate collection vehicles. It is important to the economical practice of Applicant's invention herein that such waste and refuse may be fed directly into Applicant's 45 improved incineration arrangement without prior classification, homogenization, or the like.

The feed oscillating conveyor 36 transfers the waste and refuse to a screw feed 40. While it will be appreciated that many types of screw feeds may be conveniently utilized in Applicant's invention herein, Applicant has found particular economic operation with an Archimedean screw for the screw feed means 40. That is, within the internal diameter of the screw means 40 there is provided a spiral wall and the screw means 40 is then rotated so that material is transferred within the internal diameter thereof. It is, of course, necessary that any solid waste introduced into the incineration arrangement 10 be positively conveyed into the incineration chamber 14 by the input feed arrangement 12. It is highly improbable that representative heterogeneous solids waste and refuse can be conveyed without stoppage through any feed system having an opening through which the heterogeneous solid waste must be forced. That is, such opening will, invariably, at one time or another clog to restrict or stop the flow of solid waste into the incineration chamber 14. For example, representative solid waste and refuse may contain anything from a telephone pole with climbing cleats attached thereto to a portion of a truck frame. While the input feed arrangement 12 may readily accept the telephone pole, it may become clogged because the 50 climbing cleats can hook onto the feeding arrangement 12. In 55 60 65 70 75

the event that this occurs, any solid waste behind the telephone pole must be removed before the telephone pole can be withdrawn. Similarly, in the case of a truck chassis or portion thereof, the aperture may be just too small to accept that large a piece of waste or refuse.

Applicant has found that an Archimedean screw conveyor is less subject to blockage and stoppage than most other types of conveyors and, accordingly, Applicant prefers to use an Archimedean screw in the conveyance of the waste and refuse from the input oscillator conveyor 36 to the open pit incineration chamber 14. The Archimedean screw conveyor conveys material through a revolving tubular cylinder in which there is provided an internal screw or ribbon mounted on the internal surface thereof. Such a conveyor can easily transfer material at the same level, to a greater level or a lower level than the input. It will be appreciated that the Archimedean screw conveyor provides a positive displacement up to the depth of the spiral ribbon or screw thread therein and provide surface contact conveyances for material resting above the height of the ribbon. Therefore, it is apparent, in the Archimedean screw that it can carry and convey material in either direction depending upon the direction of rotation thereof. A typical Archimedean screw conveyor 40 is illustrated in FIGS. 3 and 4. As shown on FIGS. 3 and 4 the Archimedean screw 40 comprises a cylindrical wall 42 having a screw thread or rivet 44 at a predetermined pitch and predetermined height coupled to the interior surface 46 thereof.

Waste and refuse to be burned within the incineration chamber 14 is conveyed into the Archimedean screw 40 by the input feed oscillating conveyor 36. The waste and refuse may be generally indicated as at 48 and passes through an entrance ring 50 to the interior 52 of the Archimedean screw 40, which rotates about an axis 54. Rotation of the Archimedean screw 40 in the direction indicated by the arrow 56 will transfer the waste and refuse 48 from the entrance ring 50 to the discharge end 58 thereof that is positioned within the incineration chamber 14.

The Archimedean screw conveyor provides highly economical operation when combined with Applicant's improved incineration arrangement. That is, the structure of an Archimedean screw conveyor minimizes the down time or inoperative time due to clogging or jamming. For example, if a telephone pole complete with climbing cleats is pulled into the conveyor by its rivet screw action, the operator of the conveyor can, if he desires, reject the pole by reversing the direction of rotation. The climbing cleats cannot stop this reversal as it can with other types of screw feed arrangements and, consequently follow the contour of the rivets. Therefore, the resistance to reverse drive cannot be greater than the resistance to drive from the entrance ring 50 to the discharge 58. Since the climbing cleats follow the contours of the rivet screw 44, it is easily rejected by reverse rotation. Similarly, such reversal to drive the hypothetical telephone pole in a backward direction opposite to the direction indicated by the arrow 60 which is the normal feed direction, will also move any solid waste and refuse that is behind it, over it or under it.

On the other hand, if a truck chassis has a small portion that moves from the feed oscillating conveyor 36 into the interior 52 of the Archimedean screw 40 and then has a dimension larger than the aperture 62 in the entrance ring 50 the operator can merely reverse the direction of rotation of the Archimedean screw 40 to reject the truck chassis. For example, the Archimedean screw 40 may be driven through gear means 64 coupled to the external wall surface 66 of the wall 42 by matching gear 68 rotated by electric motor 70. The electric power motor 70 is preferably operated in either direction so that the direction of rotation of the Archimedean screw 40 may be comparatively easily changed.

The Archimedean screw also uniquely controls the feed rate of material into the incinerator chamber 14. That is, by the depth of the rivet or screw thread 44, its pitch, and the peripheral speed of the Archimedean screw 40, uniquely define the feed rate. It will be appreciated that the pitch of the

rivet or screw thread 44 may be varied throughout the axial length of the Archimedean screw 40. This may provide, if desired, different speeds, heights of travel and agitation during the transfer.

5 Paddle 70 may, if desired, be attached to the rivet or screw thread 44, or to the interior wall surface 46, to increase the lifting travel height of material beyond their respective normal angles of repose. Further, such paddles often aid in reverse classification which, by definition, is the lifting of material of lowest specific gravity on top of the material of higher specific gravity. That is, in reverse classification the less dense material is on top and the more dense material is on the bottom. For example, if a brick is resting on a piece of paper between portions of the rivet or screw thread 44 and adjacent to the interior wall surface 46, during rotation the paper must continue to climb along the side of the surface 46 so long as the brick rests on it. The brick cannot climb higher nor further than the paper under it. Once the brick loses its angle of repose, the paper is then free to fall backward and, in general, will fall backward on top of the brick and the paper is not inclined to get under the brick again because it does not have the ability to penetrate a denser mass to get under it. As the paper falls away from the periphery of the wall surface 46, and goes 10 toward the interior of the interior 52, it is removed from that part of the Archimedean screw conveyor 40 with the greatest peripheral speed, hence the greatest climbing rate. Thus, free paper will tend to remain in the center resting on the top of the denser material because it has been displaced from the confines of positive physical agitation provided by the spiral rivet 44 or the lifter paddle 70.

If desired, the entrance ring 50 may be provided with air ports 72 through which secondary air indicated by the arrow 74 is fed into the interior 52 of the Archimedean screw 40. It will be appreciated that while Applicant shows the secondary air being directed through the entrance ring 50, it may be also supplied at any axial station along the Archimedean screw 40. The secondary air flow 74 tends to feed the lighter material such as paper which may be readily airborne, into the incineration chamber at a rate faster than the normal feed rate of the Archimedean screw 40 and, further, aid in the rapid combustion of such materials to products of complete combustion within the incineration chamber, as described below in greater detail.

45 As noted above, the Archimedean screw may be driven by the electric motor 71 and supported in bearings 73.

In the preferred embodiment of Applicant's invention, the entrance ring 50 is a split ring construction comprised of a first 50 half 74 and a second half 76 each of which are hinged, respectively, by the hinges 78 and 80 to appropriate supporting structure so that they may swing outwardly when desired to allow for comparatively easy reverse flow operations when the Archimedean screw conveyor 40 is operated in reverse.

55 Since the lighter material such as paper, as noted above, tends to remain along the upper surface 82 of the material contained within the interior 52 of the Archimedean screw conveyor 40, or the surface 82 which would be the level with the paddle 70 attached, it is conveyed into the open pit incineration chamber 14 by surface contact and therefore the secondary air flow 74 can accelerate the rate of travel of such materials through the feed structure.

THE INCINERATION CHAMBER

65 The incineration chamber 14 as shown on FIG. 2 has an input end 86 and a remote end 88. The Archimedean feed screw 40 transmits the waste and refuse material into the input end 86. The open pit incineration chamber 14, within the confines thereof, burns the waste and refuse, in the manner hereinafter described, to products of complete combustion.

75 FIGS. 5, 6 and 7 illustrate various sectional views of the incineration chamber 14 and FIG. 8 is a perspective view, partially in section, thereof. Referring, then, to FIGS. 2, 5, 6, 7 and 8, it can be seen that the incineration chamber 14 is com-

prised of an outer shell 90 which, according to Applicant's invention herein, may be concrete. Spaced apart inwardly therefrom is a liner wall 92 of ceramic tile for thermal refractory purposes. Thus, the walls of the incineration chamber 14 may be considered to be comprised, even though of a double wall construction, of a pair of parallel spaced-apart sidewalls 94 and 96, an input end wall 98 and a rear wall 100. The Archimedean screw 40 is positioned to transmit waste and refuse into the interior 102 of the incineration chamber 14 through the feed wall 98 adjacent to feed end 86. The waste and refuse leaves the Archimedean screw feed 40 and, except for those airborne portions thereof that are blown into the interior 102 of the incineration chamber 14, fall upon plate 104 which, in turn, transmits the solid waste and refuse to the first oscillating conveyor hearth 106 forming a portion of the base 108 of the incineration chamber 14. The oscillator conveyor hearth 106 may be of the type manufactured by Link-Belt Company under the name of "Flexmount," "Coilmount," or "Torqmount" oscillating conveyors. The oscillator conveyor hearth 106 moves the waste and refuse in a direction indicated by the arrow 110 from the front wall 98 to the rear wall 100. Reciprocating motion of the oscillating hearth 106 in the direction indicated by the double ended arrows 118 continually move the waste and refuse in the direction indicated by the arrow 110 due to the continuous feed of waste and refuse into the incineration chamber 14 from the Archimedean screw 40. A fire bed 120 is maintained on the oscillating hearth 106 and the material falling thereon and moving in the direction indicated by the arrow 110 is adapted to be burned within the confines of the incineration chamber 14. If the material is not burned to gaseous products and incombustible products after the first traversal of the incineration chamber 14 on the first oscillating hearth 106 it is recycled in a direction opposite hereto by the second oscillating hearth 122. The second oscillating hearth 122 may be similarly constructed to the first oscillating hearth 106. Similarly, the feed oscillating conveyor 36 may also be similarly constructed.

At the end of the oscillating hearth 106 adjacent to the rear wall 90 there is provided a banked turn 124 so that the normal angle of repose of the material as it is forced therearound by the continuous feed forces the as yet unburned material from the oscillating hearth 106 to the second oscillating hearth 122. The second oscillating hearth 122 moves the material in the direction indicated by the arrow 124 towards the first wall 98 where there is provided a second banked turn 130 that redirected the unburned material onto the first oscillating hearth 106 in regions adjacent the end of the plate 104. Material contained upon the oscillating hearth 106 and 122 are thus continuously recycled within the open pit incineration chamber 14 until they may be removed, as desired, through grate portions 132 in first oscillating hearth 106 or grate portion 134 in second oscillating hearth 122. The dynamics of the movable grates 132 and 134 is described below in greater detail in connection with FIGS. 9, 10 and 11.

As shown in detail in FIGS. 9, 10, 11, each of the oscillating hearths 106 and 122 are provided with moveable grates 132 and 134, respectively, to allow removal of material from the chamber 14 as may be desired. The grate 132 is mounted for reciprocating movement with hearth 106, for example, and is also mounted for reciprocating movement in the direction indicated by the arrow 200. As depicted on FIG. 11, the grate 132 has a first end 202 adjacent on edge 204 of an aperture 206 in the hearth 106. A motor 208 is coupled to the underside 210 of the hearth 106 and rotates screw drive shaft 212 in the directions indicated by the arrow 214. The screw drive shaft 212 has a threaded portion 216 engaging a nut 218 coupled to the underside 220 of the grate 206. The screw drive shaft 212 is rotatably supported in the bearings 222. Rotation of the screw drive shaft 212 moves the grate 132 in the directions indicated by the arrow 200 to open and close the aperture 206 in the hearth 106 as desired. Operation of the motor 208 may be manually controlled.

As shown in FIGS. 9 and 10, the grate 132 is supported on flanges 224 of supports 226 by wheeled guides 228. The guides 228 are coupled to cross member 230, 232 and 234 on each side thereof to control the path of movement of the grate 132.

When the grate 132 is opened, the end 236 thereof moves away from edge 238 of aperture 206 in hearth 106 and towards the edge 204 as close as desired to open up as large a portion of the aperture 206 as desired. Thus, any solid material burned to product of complete combustion or anything else in the fire bed 120 or 134 may be removed in removal pit 166.

As indicated on FIG. 9, the grate 134 may be similar to the grate 132.

A plurality of producer zone temperature measuring means such as thermocouples 140 are positioned in spaced-apart relationship adjacent the baffle means 302a on the sidewall 94 of the incineration chamber 14. As described below in greater detail, the thermocouples 140 measure the producer zone flame temperature and control the producer air flow into the interior volume of the producer zone 170 of the incineration chamber 14. The producer air flow is directed into the producer zone 170 through the plurality of nozzles 144 above the baffles 302 and, as can be seen, is downwardly and inwardly directed from the sidewall 94 toward the sidewall 96 at an angle approximately 30° to generate the vortex 147 therein. The producer zone temperature control 16 receives the signal from the producer zone thermocouple 140 and controls the nozzle 144, for example by means of a motor operated valve 146 to control the amount of producer air injected into the producer zone 170 thereby. Air is supplied to each of the nozzles 144 from common air header 148.

Additionally, a plurality of producer zone water spray nozzles 150 are provided adjacent each of the producer air nozzles 144 for directing a stream of water into the producer zone 170 of the incineration chamber 14. These producer water nozzles 150 are supplied by water header 154 and are utilized as an emergency condition to prevent any exceptionally high temperature from causing damage to the structure. For example, if a load of magnesium happened to be contained within the waste and refuse on the oscillating hearth 106, the sudden combustion of the magnesium could be deleterious to the structure without proper cooling efforts.

Ash gutters 160, 162 and 164 are positioned adjacent the longitudinal edges of the first oscillating hearth 106 and second oscillating hearth 122 as indicated in FIG. 7. These may be arranged to empty into removal pit 166 where the materials from the grates 132 and/or 134 are dumped so that they may be removed therefrom for further processing to recover any desired constituents thereof.

For clarity, the steam generator system 26 has been omitted from FIGS. 2, 5, 6 and 7. However, as indicated by the block 26 on FIG. 5, the heat exchanger for steam generator may be positioned above the open pit incinerator 14 so that the water flowing therethrough may be converted into superheated steam for operation of the steam turbine 30, as shown on FIG. 1 and as described above.

The above description of the structure associated with this embodiment of Applicant's invention is combined with a predetermined thermodynamic control to achieve the economic combustion to products of complete combustion of the combustible matter within the waste and refuse.

65 THERMODYNAMIC ZONES OF COMBUSTION

As shown most clearly on FIG. 7, according to Applicant's invention herein, there are provided two separate and independently controllable zones of combustion in Applicant's invention. That is, there is first provided the gas producer zone generally designated 170 and a furnace zone generally designated 172. The gas producer zone is a zone in which, primarily, the highest specific gravity combustibles contained within the waste and refuse fed into the incineration chamber 14 are combusted to gaseous products of incomplete com-

bustion and solid incombustibles. That is, for example, a tree stump which is a rather massive combustible that may be contained within the waste and refuse has a fairly low surface area to mass ratio, and, consequently, will make several cycles through the incineration chamber 14 before it is combusted. In the gas producer zone 170 this tree stump, for example, is burned to products of incomplete combustion and to residual ash. The base of the gas producer zone 170 may be considered to be comprised of the fire bed portion 120 and the producer zone 170 also comprising the flame portion 174. The thermocouples 140 are positioned to measure the flame 174 temperature and to control the producer air flow through producer air nozzles 144 in response thereto to maintain the flame temperature within a predetermined temperature range as described below. It will be appreciated, however, that the lighter combustible products fed through the Archimedean screw that may be airborne due to the secondary air flow 74, normally, will comprise light papers, light rags or similar very high surface area-to-mass ratio elements which are frequently burned directly to products of complete combustion within the gas producer zone and then again join the heat of reaction with carbon to rapidly make combustible gas. Thus, Applicant can equally provide a controllable different rate of progress between the fast burning and slow burning solid combustible waste and refuse during progress through the incineration chamber 14. In any event, however, both slow and fast burning solid wastes may be simultaneously reduced to mixed gases that are amenable to complete combustion when mixed with the proper amounts of air at the right temperature.

In furnace zone 172 which may be considered to comprise the region above the baffle means 302 the products of incomplete combustion are reacted to complete combustion products while escaping therethrough. The gaseous products generated within the gas producer zone 170 must, of course, escape by passing through a gas flow passage such as the orifice 310 defined by the baffle means 302 comprised of baffles 302a and 302b, coupled to interior sidewalls 94a and 96a, respectively.

A separate furnace air supply to the furnace zone 172 is provided by furnace air nozzles 304 which are independently controlled through furnace temperature control 16' operating, for example, motorized valves 306. Furnace temperature control 16' receives input signals from furnace temperature measuring means 308 which, for example, may comprise thermocouples and be substantially similar to the producer temperature sensing means 140. The furnace zone air furnished through furnace zone air nozzle 304 comes from the common air header 148. Thus, predetermined set-point temperatures may be maintained in the furnace zone 172 independently of the reactions taking place within the gas producer 170.

The baffle means 302 extend throughout the length of the incinerator chamber 14 along the interior walls 94a and 96a a predetermined shape that is generally, as far as the lower surfaces 302' thereof, arcuately concave downwards to define the upper boundary of producer zone 170. Baffle means 302 extend a predetermined distance over the base means 114. The upper surfaces 302" which define the lower boundary of furnace zone 172 are generally also arcuately concave downwards to aid in the producer air flow from producer air nozzles 144 to achieve the vortex 147. The baffle means 302 define the orifice 310 having a preselected area between the producer zone 170 and furnace zone 172. The producer zone inlet air from the producer zone inlet air nozzles 144 enters the producer zone 170 to generate the vortex 147 from above the baffle means 302. The flame 174 and gases escape from the producer zone 170 through the orifice 310 into the furnace zone 172. Thus, the baffle means 302 generally comprise the upper portion of the gas producer zone 170 but since they are coupled to the walls and preferably water cooled through apertures 302a therein, structural supports such as arches, refractories, or the like are not required and they may be fabricated from sheet metal. First walls 309 comprising the leading edges 355 and 356 of the baffle means 302 provide the

preselected area of the orifice 310 which is generally reduced from the width of the gas producer zone 170. This reduction in width provided by the preselected orifice area increases the escape velocity of the flames 174 and gases generated within the producer zone 170 entering the furnace zone 172.

A predetermined shape of the baffles 302 defined, particularly, by the lower surface 302', also provides a means for controlling the flame elongation and the shape of the flow patterns for the flow in the gas producer zone 170. It is generally preferred to provide laminar flow in order to achieve more controllable, long, luminous (reducing) flames and thereby provide more uniform temperature distribution. Such uniform temperature distribution in the producer zone adds greatly to the life of the refractory materials utilized to line the producer zone. It has also been found that the increased surface area provided by the lower surfaces 302' of the baffle means 302 as the upper boundary of producer zone 170 provides an additional impingement surface for entrained particulate matter in the gas stream that follows the periphery of the sidewalls of the producer zone 170 impinging thereon due centrifugal force exerted in the vortex 147. The shape of the baffle means 302 as shown also tend to maintain the integrity of the vortex flow pattern in order to achieve the centrifugal force upon the particulate matter.

Thus, the orifice 310 area provided by the baffle means 302 ensures an additional barrier for particulate matter and matter entrained in the producer gas to inhibit the entrance of such particulate matter into the furnace zone 172. Particulate matter that may be entrained in the producer gas laminar flow pattern, having mass, must therefore, lose inertia in order to deviate from the direction provided by the lower surfaces 302' of the baffles 302 in order to rise through the orifice 310 into the furnace zone 172. To do so, additionally, the escaping particulate matter must then further penetrate the producer air flow provided by the producer air nozzles 144. Both of these actions are difficult for the particulate matter to achieve and thus more particulate matter tends to be retained in the producer chamber for recirculation within the producer zone 170.

Thus, in this invention, independent temperature control is provided for both the producer zone 170 and furnace zone 172. This has been found to be advantageous in many applications of the invention and comprises an improvement over the invention described and claimed in the above-mentioned U.S. Letters Pat. No. 3,465,696. It will be noted that U.S. Pat. No. 3,465,696, Table VII - "Data Derived from Enthalpy-Temperature Diagram" provides an example showing the various quantities of total air required in making a product of complete combustion from solid waste having a net calorific value of 6000 B.t.u. per pound. The example demonstrates that different quantities of air provide different temperatures in both the producer zone and the furnace zone. In all cases, air metered to the producer zone was derived from total air as shown in column entitled "Total air for product of complete combustion, ft.³." The remaining air required to make a product of complete combustion at different temperatures in furnace zone is shown in Table VII under column "Air for secondary combustion, ft.³." is arbitrarily delivered to a furnace zone or may be delivered off-site for a combustible mix in such as a reverberatory furnace. While many incineration arrangements can be operated satisfactorily in accordance with the structure described and claimed in U.S. Letters Pat. No. 3,465,696, more precise control provided by the independently controllable furnace air and producer air achieves a greater level of efficiency in the incineration of a wider range of waste products. As noted below, independent temperature sensing and air metering for the furnace zone 172 reduces the mechanical complication that is brought about through arbitrary division of air in making a product of complete combustion if water or steam is used in the furnace zone to accelerate the combustion rate of particulate matter. Independent temperature sensing and air metering control provides greater latitude and less complication than provided by ar-

bitrary division of air in the zones if deviation of combustion temperature is desired in the furnace zone 172.

As noted below, in the producer zone 170 the existing ambient temperature is not normally constant but inherently varying throughout the length thereof in the incinerator 14 but the plurality of temperature sensing means 140 to control the producer air 144 allows commensurate variation in the quantity and/or velocity of the producer air in each portion of the producer zone to provide controlled steady state temperature throughout the length thereof. Similarly, air flow into the furnace 172 through the furnace air nozzles 304 may also be controlled throughout the length of furnace zone 172 through the furnace temperature control 16' detecting the temperature through furnace temperature detector 308. Thus, automatic set point temperature can be maintained or altered independently in both chambers in spite of the varying and inconsistent calorific value of the waste products being burned in the combustion zones 120.

The upper surfaces 302' and lower surfaces 302 defining the baffles 302 may be substantially equivalent on each side of the incinerator chamber 14, or, as shown in FIG. 7, they may be different to provide any air flow and/or flame pattern that may be desired depending upon the position of the producer air nozzles 144 and the like.

Additionally, water nozzles 312 for supplying emergency control water to the furnace zone 172, as shown in FIG. 7, may also be fed directly from a common water header 154 and the furnace zone nozzles 312 supply the same function for the furnace zone 172 as the producer water nozzles 150 do for the producer zone 170. The use of water in the furnace zone is more important to exploit the fact that microscopic carbon particulate matter can be gasified at a greatly increased rate in the presence of H_2O vapor. Any practical set-point temperature can be maintained in the furnace zone when H_2O liquid is added if the air quantity is reduced to compensate for the heat loss incurred in changing H_2O liquid to H_2O vapor. Reduced air quantity increases flame temperature. (See Table V - Maximum Flame Temperature of Gases in Air.)

Table VIII, above, shows the various constituents of solid waste and refuse from which are generated the, ultimately, products of complete combustion and solid incombustible products in Applicant's improved incineration arrangement

10. It will be appreciated, of course, that this representative statistical analysis of waste and refuse products need not be constant but, according to Applicant's invention herein, since the elements comprising the combustibles therein are substantially constant Applicant's thermodynamic control will automatically account for variations in the percentage constituents of calorific value and moisture content.

From Table VIII it can be seen that if 2000 pounds of the solid waste has been burned and complete combustion thereof 10 was obtained, that is, all combustible materials were burned to gaseous products of complete combustion and solid incombustibles, the solid incombustibles from the organic material would be 27.4 pounds of ash, the solid incombustibles would be 361.5 pounds from the inorganics or a grand total of 15 389.45 pounds of solid incombustibles. It will be appreciated, according to Applicant's invention herein, that these solid incombustibles are inorganic, nongasifying and may be readily used for fill material or process for reclaiming of any material constituents contained therein.

20 The function of the furnace air is to supply to the products of incomplete combustion generated within the gas producer zone sufficient oxygen so that they may be burned to products of complete combustion. However, it will be appreciated that 25 gas generated from the solid waste and refuse in the gas producing zone may evolve in various and continuously varying combination. However, since the elements comprising the solid combustibles waste products are in general known, a commonality of fuel and air may be readily attained according 30 to Applicant's invention herein. That is, a common fuel-to-air ratio may be maintained so that the proper amount of oxygen for the gases produced within the gas producer zone is supplied in the furnace zone to burn them to products of complete combustion. With the typical analysis of solid waste 35 and refuse as shown on Table VIII, Application has determined that the gases generated in the gas producer zone which must be burned to products of complete combustion in the furnace zone are carbon monoxide, hydrogen, methane and other gases of the hydrocarbon chain and hydrogen sulfide. Since these will be burned by air which is comprised generally of oxygen and nitrogen, Table XII presents the characteristics and properties of all the gases concerned in the combustion process of Applicant's improved invention.

TABLE XII
PROPERTIES OF THE GASES CONCERNED IN THE COMBUSTION OF FUELS

BASIS OF TABLE:

Oxygen content of Air = 21.00% by volume (i.e. 1 volume of oxygen in 4.76 volumes at 32°F and 760 mm Hg, 1 gram molecule of gas occupies 22.414 litres volume of one pound molecule = 359.00 ft.³)
Round values for calorific value at 30° Hg and 60°F, saturated, representing most reliable data.

For these gases, Applicant has found that a commonality of fuel and air can be obtained by maintaining a flame temperature in the range of 2000° F. to 2500° F. Thus, each of the producer air nozzles 144 is controlled by its corresponding thermocouple 140 to provide sufficient air such that the flame temperature of the flame 174 is maintained substantially with this range of 2000° F. to 2500° F.

Within this temperature range Applicant has found that any fuel-air ratio can be established and maintained that is required to reduce any of the products of incomplete combustion generated from hydrocarbon and carbohydrates within the gas producer zone to products of complete combustion in the furnace zone. It will be appreciated, of course, that different amounts of air may be flowing at any one instant of time from different producer air nozzles 144 as they are controlled by their individual thermocouples 140 to maintain immediately adjacent flame temperatures of the flame 174 at the range within 2000° F. and 2500° F. It will be appreciated that maintaining the flame temperature within this range provides a fire bed surface temperature on the order of 2000° F. The above temperature range ensures that temperatures are low enough so that dissociation of the gases will not occur to any substantial degree and that the temperature is sufficiently high to ensure their ultimate complete combustion in the furnace zone 172 by conforming to the equilibrium changes that occur at 2000° F. in the producer zone as shown in Tables III and IV, wherein common limits of inflammability are achieved for over 99 percent of the heterogeneous gases.

As indicated above, Applicant also provides the producer water nozzle 150 for directing a jet of water into the interior of the incineration chamber 14. It will be appreciated that there are rare and exotic combustible materials with intensely high flame temperatures that can enter the incinerator with other solid waste and refuse. It has been noted above that magnesium is one of these materials and, in addition, some plastics also produce extremely high flame temperatures. If insufficient air to dilute these flame temperatures to the above-mentioned range is available to the corresponding primary air nozzle, then as an emergency control, water may be directed from the nozzles 150 to quench the flame temperature. Thus, there will generally be constantly varying air requirements throughout the length of the incineration chamber 14 from the front wall 98 to the rear wall 100 thereof. This is why Applicant provides a plurality of individually controlled primary air nozzles 144. The constantly varying air requirements that are experienced in the different portions throughout the length of the incinerator chamber 14 from the front wall 98 to the rear wall 100 thereof in the producer zone vary directly with the heat content of the rubbish being gasified. This necessitated a constant variance of the producer air supply on a length basis in a moving bed of solid combustible waste and refuse products that is gasified since the heat content, moisture and constituency of the waste and refuse is not constant or homogeneous, such as experienced in traditional fuels, but constantly varies throughout each portion as it moves lengthwise through the incinerator. Therefore, the various gases generated from the waste and refuse do not have at each portion common limits of inflammability that permit a common fuel air ratio that will allow burning of the various gases generated to a product of complete combustion throughout the entire length of the incineration chamber 14 in the producer zone. That is, the fuel-to-air ratio will vary depending upon the gases produced in the particular portion thereof.

For example, waste and refuse being conveyed through one portion in the incinerator chamber 14 may have such a low calorific value that if a fixed quantity of air was introduced, the quantity of air might be so great that the flame temperature would be diluted so much that the resultant gas generated would not be amenable to be converted into a product of complete combustion with the same fuel-to-air ratio that is required to burn gases generated in another portion to a product of complete combustion.

The basis for reduction of air quantity supplied by the air nozzle 144 to increase and control the flame temperature in a gasifying bed 120 comprising low calory content or high water content waste and refuse, is the relationship of the reversible 5 carbon gas equilibrium, that is, the equilibrium between carbon monoxide and carbon dioxide and carbon, to the reversible methane-hydrogen equilibrium. If flame temperatures are made sufficiently high, though under the disassociated temperature, an identical common fuel-to-air ratio can be 10 established that will permit the gases of both equilibria to be simultaneously burned to products of complete combustion. However, it will be appreciated, that at the same time, waste and refuse that has been moved into a preceding portion in the incineration chamber 14 may have such high calorific 15 value, that a fixed quantity of air in this portion might be so insufficient and flame temperatures would be so great that the generated gases disassociate or revert to a state that does not permit the establishment of a fuel-to-air ratio that is compatible with all gases generated in the gas producer zone of this portion of the incineration chamber 14. Thus, a common fuel-to-air ratio is necessary for a simultaneous burning to a product of complete combustion.

Applicant has found that there is an approximate temperature range of 2000° F. to 2500° F., as noted above, within the heterogeneous mass of generally hydrocarbon and carbohydrates comprising the bulk of the waste and refuse as shown on Table I, can be gasified, as indicated on Table II, to the extent that a common fuel-to-air ratio can be established 25 in the furnace zone that will burn to a product of complete combustion all of the gases generated within the gas producer zone 170 of the incineration chamber 14. It will be appreciated, of course, that this is essentially a high temperature incineration process. However, only at the above stated temperature 30 are completely burned gases achieved within the pressure range of 1 atmosphere. Therefore, it is necessary if a product of complete combustion is required in incineration, to completely control and vary the quantity and preferably the velocity of air introduced into the incinerator in both the furnace zone 172 and producer zone 170. The independently 35 quantity of air supplied must be in conformity with the varying heat conditions existing in each portion of the incineration chamber 14 from the front wall 98 to the rear wall 100. Therefore, an incinerator portion as defined herein may be considered 40 to comprise the area in which a relationship exists between a producer air nozzle 144, or a grouping thereof, and the adjacent heat sensing device for generating a signal proportional 45 to the flame temperature of the flame 174 adjacent to the producer air nozzle or nozzles 144 and the control system for controlling the producer flow rate therefrom in response to such measured temperature.

As noted above, it is preferred in the embodiments of this 50 invention to provide the baffle means 302 between the producer zone and the furnace zone 172 in order to achieve independent temperature control of the producer zone 170 and the furnace zone 172 through the independent temperature 55 measurements and air flow controls. Tables XIII, XIV, XV, XVI and XVII illustrate the variations in the steady state 60 combustion temperatures that can be achieved by varying the percent of excess air for solid waste having 2,000 B.t.u.s per pound, 4,000 B.t.u.s per pound, 6,000 B.t.u.s per pound, 8,000 B.t.u.s per pound and 12,000 B.t.u.s per pound, respectively. As can be seen, virtually any desired set-point temperature 65 within the above-mentioned preselected temperature range can usually be achieved by merely varying the percentage of air. It should be noted in the above same charts that for any preselected operating temperature in the producer zone 70 170, the gas volume will increase or decrease in accordance with the increase or decrease of the calorific value of the liquid and solid waste material feedstock. Independent temperature measurement and air flow means in the furnace zone 172 meter the varying volumes of air required to make a 75 product of complete combustion of the varying volumes of

steady state set-point temperature-enthalpy gases issuing from the producer zone 170.

The present invention can also control and maintain steady state gas volume production rate as synthesized from heterogeneous liquid and solid waste which have constantly varying calorific value and/or moisture content in those applications where such control is desired. Steady state gas volume production rates can be established under the above-stated conditions in either the producer zone or the furnace zone.

Volume control is achieved by a combination of temperature and feed rate of liquid and/or solid waste control. Without temperature control and feed rate control, there generally are too many variables in moisture content and/or calorific value of liquid and solid waste to produce a predictable and controllable gas volume production rate by only varying the waste feed rate.

Consideration has been given in the past to using solid waste as a commercial fuel, in competition with homogeneous fuels such as wood, coal, liquid petroleum products and natural gas. The idea is intriguing since solid waste has an average heat value that is approximately half that of coal and it can be construed to be a "free" fuel, derived as a byproduct from the original operation. Unfortunately, solid waste inherently lacks predictability of quantity and quality, of heat value, of volume and of combustion product, which are the desirable characteristics of homogeneous fuels.

If solid fuel is to be fully exploited as a heat source, it must be made into a gaseous product that has a predictable and controllable volume production rate in addition to predictable and controllable temperature and enthalpy. Without volume control, a predictable and controllable quantity of heat units (B.t.u.s) cannot be established at any given time, or for a sustained period of time, even though the gases may have been synthesized to have a single steady state temperature and enthalpy as well as common limits of inflammability. It should be noted that steady state temperature provides steady state gas enthalpy. In general, equal gas temperatures provide equal enthalpies, regardless of the calorific value of the liquid or solid feedstock. Similarly, it is the calorific value of the liquid and solid waste feedstock going into the producer zone of the incinerator that establishes the gas volume production rate of the gas produced. High calorific value liquid and solid waste feedstock produces a high volume of gas and low calorific value liquid and solid waste feedstock produces a low volume of gas. This also applies to gases that are maintained at steady state or set-point temperature and enthalpy.

The ability to maintain steady state gas volume production rate, just as in the case of maintaining steady state enthalpy, is important if the gases are to be burned in a turbine or internal combustion engine or heat exchanged in an incinerator furnace zone.

If the gases are to be merely discharged into the atmosphere, then gas volume production rate is relatively unimportant.

At best, without the above-mentioned controls, solid waste can only provide a nonconstant and indifferent source of fuel for standby service in power generation. Without volume control, the volumetric variations in the gases derived from liquid and solid waste precluded them as a main or primary fuel source in power generation.

Gas volume production rate control is accomplished in this invention by automatically measuring the mass flow rate or velocity with such conventional instrumentation gas velocity means 350 such as a Pitot Tube, Bourdon Tube or anemometer at a location such as the leading edge 354 of the baffle 302a on the air supply side located generally between the producer zone 170 and furnace zone 172. The mass flow rate or velocity measuring instrumentation 350 generates a control signal that is proportional to the gas flow rate and is fed into gas volume control 352 which provides the feed rate volume control signal. That which is being measured by the instrumentation 350 is the volumetric gasification rate of the

producer zone. There is a direct correlation between the measured escape velocity or volume of gas leaving the producer zone 170 and the volumetric gasification rate in the producer zone 170. The Archimedean screw feed rate of solid waste

5 into the producer zone can be controlled by varying either or both the speed or depth of the conveyed load. The automatic, mechanical, electric, pneumatic or hydraulic actuation of the feed mechanism by waste feed rate control 357 in response to the magnitude of the gas volume control signal received from 10 gas volume control 352 is determined and monitored by the maximum obtainable or set-point volumetric gasification rate within the gas producer zone 170. The maximum volumetric gasification rate is predetermined by such design factors involving the fixed area of hearth gasification surface and volumetric displacement. Any set-point volumetric gasification rate below maximum is determined by variables such as the set-point operating temperature, depth of gasification bed and quantity of heat sink.

15 If the volume of gas generated in the producer zone 170 is 20 lower than the maximum or set-point volumetric gasification rate, the feeding rate is automatically speeded up to maintain maximum or set-point volumetric gasification rate. If the momentary supply of liquid and solid waste fed into the producer zone is beyond the capacity of the maximum or set-point volumetric gasification rate, the feeding rate is automatically cut back to maintain maximum or set-point volumetric gasification rate. The feed system may be provided with a regulating governor.

25 The reason why measuring the gasification velocity or volume provides the basis for an effective control in the maintenance of maximum or set-point gas volume in either the producer zone 170 or furnace zone 172, is that gas volume generated is the true measure of work accomplished in the incineration. Realistically, production rate during incineration is 30 accomplished in terms of B.t.u.s burned per ft.³/hr. B.t.u.s are an exact measurement of work accomplished, while the heat rate of typical solid combustible material fed into an incinerator process may vary in value per pound, from zero to many thousand B.t.u.s during any time interval in the incineration process. Regardless of weight, calorific value and size of combustibles fed into the process, only so many cubic feet of gas of a calorific value can be produced for a given incinerator design, involving gasifying surface, displacement, operating 35 temperature, depth of bed and heat sink. A high rate of production for combustible gas made in a reducing atmosphere is 40,000 B.t.u./ft.³/hr. It is possible to burn gas up to a rate of 40,000,000 B.t.u./ft.³/hr. However, the incineration production rate is limited to that of the gas making rate.

40 From the above, it can be seen that Applicant has provided an improved incineration arrangement. In this incineration arrangement, waste and refuse are burned to provide gaseous products of complete combustion emitted therefrom together with solid incombustible products. No preclassifying is 45 required and a pure heterogeneous refuse and waste may be rapidly combusted. By utilization of producer air to drive light weight materials such as papers and rags by an airborne state into and along the axis of the vortex generated by the producer air flow from the producer air flow nozzles 144 in the incineration chamber 14 these materials are burned at a 50 much faster rate than the materials having a much lower surface-to-mass ratio. Thus, all materials are not limited by the combustion rate of the slowest materials. According to Applicant's invention, as described above, materials are constantly 55 recirculated in the incineration chamber until they are completely gasified to gaseous products and incombustible products. Materials not amenable to rapid combustion to immediate products of complete combustion are contained 60 within a gas producing zone wherein they are gasified into combustible gaseous products of incomplete combustion and the remaining solid ash. These products of incomplete combustion then pass through an orifice and into the furnace zone where they are subjected to the independently controlled furnace air flow responsive to furnace temperature and con-

verted into products of complete combustion which, in the bulk, comprise carbon dioxide and water. This is achieved in part, by providing a plurality of spaced apart incinerator portions between the front wall 98 and rear wall 100 of the incineration chamber 14 wherein the producer air flow generating the vortex is adjusted so that the flame temperature emitted from the gas producing zone is in the range of 2000° F. to 2500° F.

This concludes the description of Applicant's invention. Those skilled in the art may find many variations and adaptations thereof and the appended claims are intended to cover all such variations and adaptations falling within the true scope and spirit of Applicant's invention.

I claim:

1. An open pit vortex incineration arrangement for burning waste and refuse comprising, in combination:

an incineration chamber having a front wall, a rear wall, and a pair of spaced apart sidewalls having top edges, and a base means;

input feed means adjacent said front wall of said incineration chamber for delivering waste and refuse into said incineration chamber through said front wall at a first predetermined feed rate;

secondary air supply means for directing a first preselected amount of air at a predetermined pressure and predetermined flow rate through said delivery means and into said incineration chamber, for moving a first preselected portion of waste and refuse therein into said incineration chamber at a second predetermined feed rate greater than said first predetermined feed rate;

said base means of said incineration chamber comprising:

a first oscillating conveyor hearth for receiving second predetermined portions of the waste and refuse thereon adjacent the front end thereof from said delivery means to transport the waste and refuse in a first direction from said front wall to said rear wall adjacent to a first of said pair of sidewalls;

a second oscillating conveyor hearth means for transporting material from said rear wall toward said front wall adjacent the second of said pair of sidewalls;

means for transferring material from said first conveyor hearth means to said second conveyor hearth means adjacent said rear wall;

means for transferring material from said second conveyor hearth means to said first conveyor hearth means adjacent said front wall;

said incineration chamber having a gas producing zone and a furnace zone, and said gas producing zone further comprising:

producer zone air supply means comprising plurality of spaced apart producer zone inlet air nozzles adjacent said first of said pair of sidewalls and spaced a predetermined distance from said base means of said incineration chamber for discharging a producer zone controlled air flow into said producer zone of said incinerator chamber at a predetermined angle to said second sidewall to generate a vortex extending substantially the length of said incineration chamber from said front wall to said rear wall and said vortex having an axis thereof substantially parallel to said base means;

a plurality of producer zone temperature measuring means, one of each of said plurality of producer zone temperature measuring means for measuring the temperature of flame emitted from said base means toward said temperature measuring means in said producer zone and generating a producer zone control signal having a magnitude proportional to said measured flame temperature;

producer zone control means for receiving said producer zone control signal and varying said producer air flow in each of said plurality of producer air nozzles in response to the magnitude of said producer zone con-

trol signal to maintain said producer flame temperature in a first predetermined temperature range, said furnace zone further comprising;

furnace air supply means comprising a plurality of spaced apart furnace air nozzles adjacent the top edge of one of said pair of side walls and spaced a predetermined distance from said furnace zone of said incineration chamber for discharging a furnace controlled air flow into said furnace zone of said incinerator chamber at a predetermined angle to the other of said sidewalls;

a plurality of furnace zone temperature measuring means, one of each of said plurality of furnace zone temperature measuring means for measuring the temperature of combustion in said furnace zone and generating a furnace zone control signal having a magnitude proportional to said measured furnace zone temperature;

furnace zone control means for receiving said furnace zone control signal and varying said furnace air flow in each of said plurality of furnace air nozzles in response to the magnitude of said furnace control signal to maintain said furnace zone temperature in a second predetermined temperature range;

baffle means coupled to said sidewalls of said incineration chamber and extending therefrom a predetermined distance overlying said base means of said incineration chamber, and said baffle means having lower surfaces defining the upper boundary of said gas producer zone, and having upper surfaces defining the lower boundary of said furnace zone, and said baffle means having first walls defining a gas flow passage between said producer zone and said furnace zone; and

removal means for removing material from said incineration chamber.

2. The arrangement defined in claim 1 wherein said delivery means further comprises:

an input oscillator conveyor for receiving the heterogeneous waste and refuse;

a screw feed means adjacent said input oscillating conveyor means for receiving said heterogeneous waste and refuse therefrom and transmitting same to said incineration chamber; and

said baffle means further comprises a preselected shape and said lower surface arcuate concave in said producer zone, and having water cooling channels extending throughout the length thereof intermediate said lower surface and said upper surface and said baffle means coupled to said sidewalls and said first walls of said baffle means defining said gas flow passage further defining an orifice and said orifice having a predetermined area comprising said gas flow passage between said gas producer zone and said furnace zone.

3. The arrangement defined in claim 2 wherein:

said screw feed means comprises an Archimedean screw; and

said preselected area of said orifice defined by said baffle means defines a laminar flow pattern control for flame and gases emitted from said producer zone to said furnace zone.

4. The arrangement defined in claim 2 and further comprising:

a plurality of incandescent solids positioned upon said first conveyor hearth and said second conveyor hearth defining a fire bed having a predetermined thickness;

said producer zone air inlet nozzles are positioned above said baffle means and said baffle means having said top surface for directing said producer zone air flow into said producer zone through said orifice defined by said baffle means;

said fire bed and said producer flame comprising a gas producing zone for combusting at least some of said combustible products in said waste and refuse to gaseous

products of incomplete combustion in said producer zone; and
said gaseous products of incomplete combustion passing through said orifice defined by said baffle means into said furnace zone and reacting with said furnace air to provide products of complete combustion.

5. The arrangement defined in claim 4 wherein said first oscillating hearth and said second oscillating hearth each have a portion thereof comprising a grate means, and said grate means comprising said removal means.

6. The arrangement defined in claim 5 wherein:
each of said first and said second oscillating hearth means comprise edges defining an aperture therethrough;
each of said grate means movably mounted on one of said first and said second oscillating hearth means for reciprocal motion therewith and movable with respect thereto to selectively open and close said aperture; and
motion producing means for moving each of said grate means.

7. The arrangement defined in claim 6 wherein said motion producing means comprises:

a motor mounted on said oscillating hearth;
a screw drive means rotated by said motor and having a threaded portion;
a nut means coupled to said grate means for threadingly engaging said threaded portion of said screw drive means; and
guide means for guiding said grate means, whereby rotation of said screw drive means moves said grate means with respect to said oscillating hearth.

8. The arrangement defined in claim 7 wherein said guide means comprises:

a plurality of wheeled guide members mounted on said grate means;
a support means mounted on said oscillating hearth and having a flange portion extending the length of said grate means; and
said flange portion engaging said wheeled guide members.

9. The arrangement defined in claim 1 and further comprising:

gas volume production rate control means for controlling the gas volume production rate of gases produced in said gas producer zone.

10. The arrangement defined in claim 9 wherein said gas volume production rate control means comprises:

gas flow rate measuring means for measuring the rate of flow of gases from said gas producer zone into said furnace zone;

5 gas volume control means for generating a volume control signal having a magnitude proportional to the measured gas flow rate; and

waste feed rate control means for varying the waste feed rate into said incineration chamber in response to said gas volume control signal.

10 11. The arrangement defined in claim 10 wherein said delivery means further comprises:

an input oscillator conveyor for receiving the heterogeneous waste and refuse;
a screw feed means adjacent said input oscillating conveyor means for receiving said heterogeneous waste and refuse therefrom and transmitting same to said incineration chamber; and

said baffle means further comprises a preselected shape and said lower surface arcuate concave in said producer zone, and having water cooling channels extending throughout the length thereof intermediate said lower surface and said upper surface and said baffle means coupled to said sidewalls and said first walls of said baffle means defining said gas flow passage further defining an orifice and said orifice having a predetermined area comprising said gas flow passage between said gas producer zone and said furnace zone.

12. The arrangement defined in claim 11 and further comprising:

30 a plurality of incandescent solids positioned upon said first conveyor hearth and said second conveyor hearth defining a fire bed having a predetermined thickness;
said producer zone air inlet nozzles are positioned above said baffle means and said baffle means having said top surface for directing said producer zone air flow into said producer zone through said orifice defined by said baffle means;

35 said fire bed and said producer flame comprising a gas producing zone for combusting at least some of said combustible products in said waste and refuse to gaseous products of incomplete combustion in said producer zone; and

40 said gaseous products of incomplete combustion passing through said orifice defined in said baffle means into said furnace zone and reacting with said furnace air to provide products of complete combustion.
